AUTOMOBILE TIRE

Paul J. Felker, Marshfield, Wis., assignor to Penetred
Corporation, Marshfield, Wis.

Filed Jan. 26, 1970, Ser. No. 21,069

Term of patent 14 years

Int. Cl. D12—15

U.S. Cl. D90—20

Fig. 1

Fig. 2

FIG. 1 is a frontal perspective view of an automobile tire showing my new design, it being understood that the detailed portion is repeated throughout the tread circumference of the tire; and

FIG. 2 is an enlarged fragmentary sectional view showing fragments of three rider strips, the rider strip on the right being the rider strip which is on the right hand side of the circumferential center line of the tire, the intermediate rider strip being the rider strip which is on the left hand side of the circumferential center line of the tire, and the rider strip on the left of FIG. 2 being one of the other rider strips.

The characteristic feature of my design resides in the design of the tread pattern.

I claim:

The ornamental design for an automobile tire, substantially as shown and described.
